Merrill E. Hansen, Akron, Ohio, assignor to
American Anode Inc., Akron, Ohio, a corpora-
tion of Delaware

Application April 6, 1940, Serial No. 91,512

Term of patent 14 years

To all whom it may concern:

Be it known that I, Merrill E. Hansen, a citizen
of the United States, residing at Akron, in
the county of Summit and State of Ohio, have
invented a new, original, and ornamental Design
for an Aviator's Oxygen Mask or Similar Article,
of which the following is a specification, refer-
ence being had to the accompanying drawing,
forming a part thereof.

In the drawing, Fig. 1 is a front elevational

view of an aviator's oxygen mask or similar article embodying my new design;

Fig. 2 is a side elevational view of the mask
of Fig. 1;

Fig. 3 is a rear elevational view of the mask
of Fig. 1.

I claim:

The ornamental design for an aviator's oxygen
mask or similar article, as shown.

MERRILL E. HANSEN.
